UNITED STATES PATENT OFFICE.

EDWARD DAYTON ROCKWELL, OF JACKSONVILLE, FLORIDA.

SASH-FASTENER.

SPECIFICATION forming part of Letters Patent No. 352,099, dated November 2, 1886.

Application filed August 7, 1886. Serial No. 210,340. (No model.)

To all whom it may concern:

Be it known that I, EDWARD DAYTON ROCKWELL, a citizen of the United States, residing at Jacksonville, in the county of Duval and State of Florida, have invented a new and useful Improvement in Sash-Holders, of which the following is a specification.

My invention relates to improvements in sash locks and holders; and it consists of the peculiar construction and arrangement of the various parts for service, substantially as hereinafter fully set forth, and particularly pointed out in the claim.

The primary object of my invention is to provide a simple and inexpensive device for holding and locking the movable sashes of windows, which shall effectually obviate the danger common to devices of this class of scratching or defacing the painted or otherwise ornamented surface of window frames or stops, to which windows the device may be applied.

In the accompanying drawings, which illustrate a sash holder and lock embodying my invention, Figure 1 is a side view showing it adjusted as a lock; and Fig. 2 is a like view, showing a modified form of base-plate. Fig. 3 is another view, showing the swinging arm reversed to adapt the device for use as a sash-holder. Figs. 4, 5, and 6 are views, in side elevation, of my improved sash-holder, illustrating modified forms of base-plates. Figs. 7 and 8 are side views of another form of my invention, showing it applied to a horizontally-sliding sash. Fig. 9 is a detail view of the base-plate shown in Fig. 1. Fig. 10 is a like view of the base-plate shown in Fig. 5. Fig. 11 is an edge view of the device shown in Fig. 1. Fig. 12 is an edge view of the device shown in Fig. 5.

Referring to the drawings, in which like letters of reference denote corresponding parts in all the figures, A designates a base-plate having shoulders a' ; B, a swinging arm permanently connected to the plate, and C a stop-casting affixed to the window frame or casing, and either end of the swinging arm is adapted to come in contact with one of the curved faces thereof, so as to adapt the device for locking the sash or holding it in an elevated position.

Referring more particularly to Figs. 1 to 3, inclusive, the base-plate is provided with the

shoulders a' , which project outwardly therefrom on opposite sides of the center thereof, and the swinging arm is pivotally connected to the base-plate between the said shoulders a' . The plate is circular, square, or of other desired form, and it is cast in a single piece of metal, and near its edges it is provided with two or more transverse openings, a^2 , which have beveled sides, through which are passed the screws that secure the base-plate to the window, the heads of the screws entering the countersunk openings, so that they lie flush with the outer face of the base-plate, and are thereby arranged out of the path of the swinging arm B, to permit the latter to oscillate or turn freely on its pivot.

The swinging arm B is permanently attached to the base-plate by means of a headed or other pin, e , which passes through a suitable opening in the arm and the plate; and the lower end of the arm is tapered longitudinally and terminates in a point, e' , while the upper end is enlarged and curved outwardly, so that the upper side is arranged out of line with the tapered lower end, as clearly shown in Fig. 11, thereby providing a finger-piece, against which the fingers are pressed to turn or shift the arm on its pivot, and thus throw either one end or the other nearer to the window-frame. The upper edge of the enlarged upper end of the swinging arm is curved inwardly and downwardly, as shown, to form the curved ears e^2 , the outer one at the upper corner being adapted to take under an outwardly-bulged shoulder, e , on the fixed stop C, in order to adapt the device as a lock for the sash, to prevent movement or play thereof. The stop C is also cast or formed of a single piece of metal, and its outwardly-bulged shoulder e has a gradually-inclined side, e' , and an abrupt side, e^2 , which is arranged at an obtuse angle to the inclined side e' , as clearly shown.

The base-plate A and the stop C are each provided with two or more transverse openings or perforations, a^2 , through which are passed suitable securing or fastening screws, to affix the device in proper position to the sash and frame of a window, and by this means the device can be easily and quickly applied by an unskilled person to the sash and frame.

The base-plate can be of preferred form, and

in the several figures I have shown different shapes, the one shown in Figs. 1 and 9 being circular, while the plate shown in Figs. 2 and 3 is square, or substantially so.

5 In applying my improved device upon a window for use, I first affix two or more of the stops C to the frame, one being located near the base or sill of the window, with the abrupt side of its shoulder lowermost, and the others 10 at points on the frame above the lower stop at the points where it is desired to elevate the window-sash, and with their abrupt sides c^2 uppermost. The base-plate and its attached arm are now applied to the sash at any suitable point thereon, preferably near the lower edge, so that the end, whether the upper or lower end, nearer to the frame will not come in contact with the frame to injure or deface the painted or otherwise ornamented surface 15 thereof. The ends of the arms are prevented from coming in contact with the painted surface of the frame by the sides thereof coming in contact with the offsets or shoulders on said plate, and are held in contact there- 20 with by the heavier upper end of the swinging arm. Thus it will be seen that when the device is adjusted for use as a sash-lock (shown in Fig. 1) the upper counterweighted or heavier end of the swinging arm is turned outward, 25 so that it is nearer to the lower stop C, and its outer upper ear, c^2 , will take beneath the abrupt shoulder on the said stop; and in this position the inner side of the lower pointed end of the arm will impinge or bear against 30 the lower side of the shoulder a' , while the outer side of the upper heavier end will bear or impinge upon the upper side of the shoulder a . By thus disposing the arm with relation to the shoulders on the base-plate so that 35 its opposite sides are in contact with the shoulders or offsets, the swinging arm is very materially braced, and is better calculated to resist the strain and force exerted on the window-sash when a burglary is attempted, and thus 40 provides a stronger and more efficient lock.

When the device is adapted for service as a sash-holder, the position of the swinging arm is reversed from the position shown in Fig. 1 to that shown in Fig. 2. In this latter figure 45 (2) the heavier upper end of the arm is forced to one side away from the frame, and the lower pointed end is forced nearer to the frame, and the outer side of the lower pointed end of the arm is in contact with the under side of the 50 stop-shoulder a , while the inner side of the upper heavier end impinges upon the upper side of the offset a' ; the lower pointed end of the arm taking against the abrupt upper side of the shoulder on the stop C, located on the 55 frame at the point where it is desired to maintain the sash in an elevated position.

In operation the swinging arm is reversed or thrown from beneath the shoulder in order to release the window to raise the latter, and 60 when it is being raised the lower pointed end will ride against the inclined side e' of the stop-shoulder of the upper stop C, until the

end passes it, when it will take upon the abrupt side of the said shoulder and retain the sash in an elevated position. To lower the 70 sash the swinging arm is first reversed to throw its pointed end away from the stop, and when the heavier end of the arm impinges against the inclined side e' of the lower stop the arm will be oscillated or thrown to nearly 75 a vertical position until the heavier end passes the shoulder, when said end will automatically drop beneath the abrupt side of the shoulder to lock the sash.

It will thus be seen that after the swing- 80 ing arm has been once adjusted to raise or lower the sash it does not require further manipulation on the part of the operator, but will automatically engage with the stop, and thus leave both of the operator's hands free to 85 raise or adjust the sash; and, further, that the ends of said arm are prevented from scraping and defacing the painted surface of the frame while they are passing up or down between the stops that are fastened to the window-frame, 90 before referred to.

In Figs. 4, 5, 6, 10, and 12, inclusive, I have shown other forms of devices contemplated by my invention. The base-plates are cut away on their lower sides to form the shoulders $a a'$ 95 on opposite sides of the arm, and the arm has a stud or lug, g , which projects or works on the cut-out portion of the base-plate, and is adapted to alternately come in contact with the said shoulders, to limit the movement of 100 the arm in either direction. The operation of these devices is substantially the same as the device shown in Figs. 1 and 2, and will be readily apparent to those skilled in the art.

In Figs. 7 and 8 I have shown my invention 105 adapted to lock a horizontally moving or sliding sash. The base-plate is affixed to the sash so that the arm lies in a horizontal position, and the heavier end thereof drops down below the center, so that it is adapted to take behind the abrupt side of the shoulder on the stop to lock the sash against movement in one direction, the upper shoulder, a' , on the base-plate serving to limit the movement of the 110 arm, so that the lower side of the heavier end 115 will be held from contact with the painted surface of the sill, to prevent scratching the same.

I attach especial importance to the base-plate having the offsets or shoulders, combined with a swinging arm pivoted to the base-plate 120 between the shoulders thereon, as therein lies the gist of my invention.

In lieu of the stops C, a screw, nail, or other equivalent device may be used; but I prefer to employ the stop in the form shown, as it 125 provides a neat and ornamental fixture, and adapts the arm to ride freely over it in adjusting the sash.

Slight changes in the form and proportion of parts can be made without departing from 130 the principle of my invention; also, when space between the window-sash and inside blinds will permit, or when inside blinds are not used, a knob or more projection can be

added to the heavy end of the swinging arm, thereby utilizing the end of said arm as a lift for perpendicular and a pull or draw handle for horizontally-moving sashes.

5 Having thus fully described my invention, what I claim as new, and desire to secure by Letters Patent, is—

A sash holder and lock consisting of a base-plate having the stop-shoulders a a' , a swing-
10 ing arm pivoted centrally to the base-plate, be-
tween the stop-shoulders thereof, and nor-
mally in contact therewith, and having an en-

larged end, and a fixed stop, against which the ends of the swinging arm impinge, sub-stantially as described, for the purpose set 15 forth.

In testimony that I claim the foregoing as my own I have hereunto affixed my signature in presence of two witnesses.

EDWARD DAYTON ROCKWELL.
